UNITED STATES PATENT OFFICE.

HERMAN K. BAYER AND HENRY J. EPSTEIN, OF ST. LOUIS, MISSOURI.

BRAKE CONSTRUCTION FOR SOLE-CUTTING MACHINES.

Application filed April 11, 1925. Serial No. 22,304.

This invention relates to brake mechanism, and has for its object to improve the construction of brake shown in our pending application Serial No. 729,689, filed August 5 2, 1924.

In the device of said application, a resilient brake band is shown surrounding a drum, and which is adapted to be released from engagement with the drum by separating its ends. The brake band is mounted on a slidable casting, so that as the ends of the brake band are separated, the casting may move away from the drum to carry the part of the band secured to the casting out 10 of contact with the brake drum. While this arrangement is entirely operative, it has the disadvantage that the points adjacent the opposite ends of the casting become weakened by use, and after a greater or less 15 length of time, will break off.

To remedy the above defect, we have devised the construction of the present invention, in which a pair of brake shoes are substituted for the single resilient brake band of our prior application, these brake shoes being non-resilient and forming, when in engagement with the brake drum, substantially a continuous circular band. Each of the brake shoes is mounted at one end on a casting which, in turn, is pivotally mounted on a slidable support. The opposite ends of these brake shoes are designed to be opened and closed in the same manner as described in our prior application, and in 30 the opening operation, the shoes are bodily moved from engagement with the brake drum and their support will slide outward to permit of the disengagement of the fixed ends of the brake shoes from engagement 35 with the drum. We do not find it necessary to employ a spring to permit this disengagement, as in our prior application, the act of separating the brake shoes simultaneously 40 causing an outward movement of their support.

The invention is illustrated in the accompanying drawing, in which—

Figure 1 is a view of the lower part of a sole-cutting machine such as shown in our prior application, illustrating the brake drum and our improved brake mechanism connected therewith;

Figure 2 is a broken elevational view showing, on an enlarged scale, the mechanism at the right of Figure 1; and

Figure 3 is a sectional view taken on the line 3—3 of Figure 1.

While our improved brake device is particularly adapted, as in the case of our prior application, for use in connection with sole-cutting machines, it could be as well employed in other connections, and hence we have illustrated only the lower part of a sole-cutting machine to bring into view a rotary drum whose motion is to be arrested.

Referring now to the drawing, the numerals 1 indicate standards of an end frame 2 of a machine having a driven shaft 3 on which is mounted a brake drum 4. Mounted at one side of a standard 1 is a rectangular stud 5 on which is slidably supported a casting 6 through the medium of a slot 7. Said casting has reduced lateral extensions 8, preferably formed integral therewith, on which are pivotally mounted, at points indicated by the numerals 9, the bifurcated ends 10 of two brackets 11, 12, respectively, which are preferably riveted, as indicated at 13, to the outer sides of the inner end portions of two substantially semi-cylindrical brake shoes 14, 15, respectively. The brake shoes 14, 15 are designed to embrace the drum 4 practically around its entire circumference, and have secured to their outer end portions, opposite to those just described, two castings 16, 17, respectively, to which are pivotally connected at points indicated by the numerals 18, two rods 19 and 20, the lower ends of which are pivotally secured at 21, 22, respectively, to the opposite ends of a rocking member 23, clamped on a lever arm 24 which is, in turn, secured on the end of a rock shaft 25, mounted at one side of the machine in the standards 1. This rock shaft is adapted to be turned to move 95 the rod 19 upward and draw the rod 20 downward and thus separate the brake shoes 14, 15 by the operator pressing down on the treadle 26, the inner end of which is secured to the rock shaft, and the outer end of which projects beyond the machine to a position giving easy access to the foot of the operator. A spring 27 is connected at one end to this treadle and at its upper end to the frame of the machine, and operates to raise 105 the treadle to apply the brake shoes whenever the foot of the operator is removed from the treadle. The two castings 16, 17 are preferably connected by a coil spring 28, which adds its force to that of the spring 27

in moving the brake shoes into engagement with the drum 4.

As previously stated, the brake shoes 14, 15 are rigid, or non-resilient, and when the treadle 26 is moved down to separate them, the two brackets 11 and 12 move in opposite directions on their pivots 9 and the force applied to thus separate the brake shoes also acts to move the casting 6 outward on the stud 5, thereby moving the fixed ends of the brake shoes from engagement with the drum. When the treadle is released and the springs 27 and 28 draw the brake shoes into engagement with the drum, the opposite movement 15 of the casting 6 occurs.

By the above construction, no bending of the brake shoes 14, 15 occurs, and hence there is no liability of breakage at the point of connection with the brackets 11 and 12, as in our prior device referred to.

We claim:

1. In combination with a rotatable brake drum, brake mechanism for arresting the motion of the same comprising a movable support adapted for movement only in a direction radial with respect to said drum, a pair of brackets pivotally mounted on said support and having portions movable toward and from each other, a pair of semi-cylindrical brake shoes surrounding said brake drum and secured at adjoining end portions to the respective brackets, means for separating the opposite adjoining end portions of said brake shoes to effect disengagement of the brake shoes from the drum, and automatic means for returning the brake shoes into engagement with said drum.

2. In combination with a rotatable brake drum, brake mechanism for arresting the motion of the same comprising a slidable support adapted for movement only in a direction radial with respect to said drum, a pair of brackets pivotally mounted on said support and having portions movable toward and from each other, a pair of semi-cylindrical brake shoes surrounding said brake drum and secured at adjoining end portions to the respective brackets, means for separating the opposite adjoining end portions of said brake shoes to effect disengagement of the brake shoes from the drum, and automatic means for returning the brake shoes into engagement with said drum.

3. In combination with a rotatable brake drum, brake mechanism for arresting the motion of the same comprising a slidable support adapted for movement only in a direction radial with respect to said drum, a pair of brackets pivotally mounted on said support and having portions movable toward and from each other, a pair of semi-cylindrical brake shoes surrounding said

brake drum and secured at adjoining end portions to the respective brackets, means connected with the opposite ends of said brake shoes and movable in opposite directions to effect disengagement of the brake shoes from the drum, a treadle operatively connected with said means and operating, upon depression, to release engagement of the brake shoes and, upon upward movement, to effect engagement of the brake shoes with the drum, and means for causing said treadle to be raised upon release thereof.

4. In combination with a rotatable brake drum, brake mechanism for arresting the motion of the same comprising a slidable support, a pair of semi-cylindrical brake shoes substantially surrounding said brake drum and pivotally mounted at adjoining end portions on said support in a manner to permit the adjacent ends thereof to move toward and from each other, means operable at will for separating the opposite adjoining end portions of said brake shoes to effect disengagement thereof from the drum, and automatic means for returning the brake shoes into engagement with said drum.

5. In combination with a rotatable brake drum, brake mechanism for arresting the motion of the same comprising a slidable support, a pair of semi-cylindrical brake shoes substantially surrounding said brake drum and pivotally mounted at adjoining end portions on said support in a manner to permit the adjacent ends thereof to move toward and from each other, means operable at will for separating the opposite adjoining end portions of said brake shoes to effect disengagement thereof from the drum, automatic means for returning the brake shoes into engagement with said drum, and a spring connecting the other opposite adjoining end portions of said brake shoes and tending to draw said end portions together.

6. In combination with a rotatable brake drum, a pair of brake shoes substantially surrounding said brake drum, slidable means at one side of the drum with which adjoining end portions of said brake shoes are movable, means operable at will for separating the other adjoining end portions of the brake shoes and thereby bodily moving the first mentioned end portions out of engagement with the brake drum, and automatic means for returning the brake shoes into engagement with said drum, the first mentioned adjoining end portions of the brake shoes being capable of movement toward and from each other.

In testimony whereof, we have hereunto set our hands.

HERMAN K. BAYER.
HENRY J. EPSTEIN.
